UNITED STATES PATENT OFFICE.

GEORGE ADSIT, OF PATERSON, NEW JERSEY, ASSIGNOR TO BENJAMIN EASTWOOD COMPANY, OF PATERSON, NEW JERSEY, A CORPORATION OF NEW JERSEY.

WARPING MACHINE.

Application filed October 6, 1921. Serial No. 505,719.

To all whom it may concern:

Be it known that I, GEORGE ADSIT, a citizen of the United States, residing at Paterson, in the county of Passaic and State of New Jersey, have invented certain new and useful Improvements in Warping Machines, of which the following is a specification.

This invention relates to warping machines of the class in which the carriage for the reeds and warp guiding rolls is traversable crosswise and arranged at one end of the frame. The invention has for its principal objects to mount the carriage so that it may be moved with considerably greater freedom than heretofore, both when traversed automatically and when reset manually; to simplify the construction of and the manipulations necessary to operate the disconnection connection between the carriage and its rotary feed-screw or worm; and to provide an improved form of gage for determining the resetting positions of the carriage when the machine is used for section-warping.

In the drawings,

Figure 1 is a side elevation of the reed-carriage end of a warping machine constructed according to the invention;

Figure 2 is a plan of what is shown in Fig. 1;

Figures 3 and 4 are sectional views on the lines 4—4 and 3—3 of Figs. 4 and 3, respectively;

Figure 5 shows a detail; and

Figure 6 is a view illustrating principally the gage, which appears in side elevation.

a is the frame of the machine having suitably fixed in arms *b* projecting therefrom the horizontal transverse round rod or shaft *c*, and also having below this shaft a horizontal transverse brace-rail or strut *d* which is in the present case a channel-rail with its open side outward and forms a part of the frame proper.

The carriage for the reeds and warp guiding rolls is constructed as follows: *e* is the hollow box-like body-portion of a casting which includes spaced arms *f* projecting forward from said body-portion at the sides thereof and bored at *g* in alignment with each other to receive the shaft *c*, each arm being further provided with a

rearward and upwardly inclined slot *h* extending from said bore. In the slot of each arm is journaled a roller *i* having a peripheral groove of a cross-section to substantially conform with that of shaft *c*. To the front faces of the arms, which are planed off smooth to the same vertical plane, is secured a vertical plate or apron *j*, to which further reference will be made. Upon the carriage is secured, as by screws *k* or in any other way, a long plate-like structure *l* which extends well outward of the carriage in the usual way and is adapted to carry the reeds and also the rolls for guiding the warp; these latter are not shown. The carriage further has a long downward leg *m* which is in the form of a skeleton casting of general triangular form and is bolted to the under side of the body-portion *e* of the carriage. On a vertical stud *n* secured in and projecting from the lower end of this leg is journaled a roller *o* adapted to bear on the guideway which is formed by the edge of one of the flanges (here the upper one) of the rail or strut *d*. Connecting the stud and the free end portion of the structure *l* is a brace *p*, being suitably secured rigidly to both of them.

The carriage, receiving the guide-rod in its bores *g*, is supported principally by the contact of roller *i* upon the guide-rod, which forms a main guideway extending transversely of the machine and facing upwardly and also rearwardly, so that nearly all of the force of gravity acting on the carriage (to wit, both directly downward and indirectly as the result of the center of gravity of the carriage being outward of the guide-rod and the carriage having a purchase or fulcrum at *d*—*o*) is opposed by said guide-rod. In consequence of this construction and arrangement the carriage is movable with the greatest freedom along the guideway. In ordinary warping machines the carriage is usually arranged to travel on two guide-rods arranged in a horizontal plane or otherwise so that the force of gravity acting on the carriage is opposed by both guide-rods substantially equally, which sets up a binding so considerable that even if anti-friction means is employed it requires considerable exertion on the part of the attendant to move the carriage by hand when resetting and for transmitting the

power necessary for traversing the carriage automatically the transmission gearing has to be designed with special regard to the resistance thus presented.

- 5 To take up any lost-motion which might exist in the bores *g* between the guide-rod and carriage and which might manifest itself if the warper pushed backwardly on the carriage with sufficient force as he 10 manually shifted it along the guide-rod *c* I provide rollers *q* which are journaled in the forked inner ends of cylindrical blocks *r* that are arranged in bores *s* extending from the front faces of the arms *f* inward 15 to the respective bores *g*, said blocks being adapted to be adjusted to bring the rollers *q* against the guide-rod by set-screws *t* tapped into lateral ears *u* projecting from the apron *j*.
- 20 The apron has a hub *j'* in which is journaled the hollow spindle *v* of a worm-wheel *w* in mesh with the worm *x* suitably journaled in the frame of the machine and adapted to be driven in warping from the 25 reel or other going part thereof by any well known means (not shown;) to keep the worm against springing away from the worm-wheel an inwardly projecting portion of the apron has suitably secured therein a 30 saddle piece *y* formed with a grooved seat for the worm. The spindle of the worm-wheel has a suitable handle *z* fixed thereon whereby to turn the worm-wheel and so feed the carriage, as in resetting, manually.
- 35 There is a novel screw-and-nut device for 40 clamping the worm-wheel against turning in the carriage, so that the rotating worm will cause automatic traverse of the carriage. The inner face of the worm wheel has a conical recess *w'* in which is set a conical nut *2* which is kept from turning and also retained in place by an arm *3* which is secured to the carriage and has its 45 free end engaged between lugs *2'* on the nut. The screw of said device consists of a threaded spindle *4* having a threaded engagement at one end with the nut and a handle *4'* at the other. When the screw is turned in one direction said device obviously 50 binds the worm-wheel in the carriage against turning, and when the screw is turned in the other direction the worm-wheel is left free to rotate.
- 55 In one of the ears *u* is arranged a longitudinally and horizontally slidable rod *5*, which may be secured at any position to which it is moved by a set screw *6*. On the guide-rod *c* a collar *7* is adapted to be secured at different stages by a set-screw *8*.
- 60 This collar has a forwardly projecting pair of arms *9* *10*, the arm *10* having a lug *10'* which is adapted to overhang the rod *5*. In the two arms *9* *10* is pivoted on a transverse horizontal axis an abutment device *11* 65 having a thumb piece *12* that is adapted to

contact with a shoulder on the collar formed at *13* and thereby form a stop to the upward pivotal movement of the abutment device. In section warping the rod is fixed in the carriage so as to project therefrom a distance corresponding to the width of the sections to be warped. The carriage being then placed at the point for starting the winding on of the first section, the collar *7* is shifted on guide-rod *c* until, the attendant having elevated the abutment device *11*, the latter contacts with the end of the rod *5*, whereupon the collar is secured in its new position. The warping of the first section is now proceeded with, and when it is completed the warper returns the carriage, which has meanwhile been traversed automatically to the right, until the side of *f* contacts with the near end of the collar *7*, abutment device *11* having been allowed to fall to the position shown in the drawings; the return movement of the carriage is equal to the traverse length plus the width of the section, the latter being determined by the extent to which rod *5* is adjusted to project to the left. Then the collar *7* is released and, being kept from falling by the lug *10'* resting on rod *5*, it is moved to the left until the abutment device can be again elevated and made to bear against the end of the rod *5*, whereupon it is secured to the guide-rod in readiness for gaging the next resetting movement of the carriage. So far as I am aware, it is broadly new to provide a gaging member, as *5*, adjustable laterally of and in the carriage to different positions, a carrier member, as *7*, settable laterally of the carriage and in the frame to different positions and adapted to be abutted by the carriage, and a detent device, as *11*, movable in the carrier member into and out of the path of the gaging member and when in said path adapted to be abutted thereby.

Having thus fully described my invention, what I claim as new and desire to secure by Letters Patent is:—

1. A warping machine including, in combination, with a frame having at one end a main horizontal guideway extending transversely and facing upwardly and also inwardly and also having below the main guideway another transverse horizontal guideway, a carriage having its center of gravity outward of both guideways and also having a bearing upon the upwardly and inwardly facing portions of the first guideway and also a bearing on the other guideway.

2. A warping machine including, in combination, with a frame having at one end a main horizontal guideway extending transversely and formed in cross-section with a convex guiding face facing in an upward inclined direction over the frame and also

having below the main guideway another transverse horizontal guideway, a carriage having its center of gravity outward of both guideways, and a roller journaled in the carriage on an axis substantially perpendicular to said incline and inward of the main guideway and having a concave periphery approximately fitting and bearing against said guiding face, said carriage also having a bearing on the other guideway.

3. A warping machine including, in combination, with a frame having a transverse horizontal guideway, a worm journaled in the frame and extending parallel with said guideway, a toothed member in the carriage engaged with the threading of the worm, and a saddle in the carriage bearing against the worm at a point opposite said toothed device.

20 4. A warping machine including, in combination, with a frame having a transverse horizontal guideway, a worm journaled in the frame and extending parallel with said guideway, a worm-wheel revoluble in the carriage and engaged with the threading of the worm, a nut-and-screw device for clamping the worm-wheel against turning in the carriage, the screw of said device penetratin the worm-wheel axially, and an arm on

the carriage holding the nut of said device 30 against turning.

5. A warping machine including, in combination, with a frame having a transverse horizontal guideway, a worm journaled in the frame and extending parallel with said 35 guideway, a worm-wheel revoluble in the carriage and engaged with the threading of the worm, a nut-and-screw device for clamping the worm-wheel against turning in the carriage, the screw of said device penetratin 40 the worm-wheel axially and the nut being recessed into said worm-wheel, and an arm on the carriage holding the nut against turning and in the worm-wheel.

6. A warping machine including, in combination, with a frame having a transverse horizontal guideway, a carriage movable along said guideway, a gaging member adjustable laterally of and in the carriage to different positions, a carrier member settable 50 laterally of the carriage and in the frame to different positions and adapted to be abutted by the carriage, and a detent device movable in the carrier member into and out of the path of the gaging member and when in said 55 path adapted to be abutted thereby.

In testimony whereof I affix my signature.
GEORGE ADSIT.
